UNITED STATES PATENT OFFICE.

RICHARD J. KELLY, OF SYRACUSE, NEW YORK.

BED-SPRING.

1,088,996.

Specification of Letters Patent.

Patented Mar. 3, 1914.

Application filed June 30, 1913. Serial No. 776,530.

To all whom it may concern:

Be it known that I, RICHARD J. KELLY, a citizen of the United States, residing at Syracuse, in the county of Onondaga and State of New York, have invented certain new and useful Improvements in Bed-Springs, of which the following is a specification.

This invention relates to improvements in bed springs, and has for its object to provide a novel, simple and effective tension and adjusting mechanism in connection with the fabric which supports the mattress. And a further object is to provide a novel frame which supports the tension and adjusting parts.

The features and parts of the invention will be understood from the detail description which follows, and by reference to the accompanying drawing which forms a part 20 of the specification, and in which—

Figure 1 is a top plan view of the complete bed spring, with parts broken away; showing the construction, arrangement and operation of my improvement. Fig. 2 is a 25 vertical longitudinal section, taken substantially on line 2—2 of Fig. 1. Fig. 3 is an enlarged detail view of one of the adjusting levers. Fig. 4 is a top plan view of the same. Fig. 5 is a fragmentary plan view; 30 showing a modification of the tension means.

Similar characters of reference are assigned to corresponding parts throughout the several views.

In the drawing, 2 represents the side rails, 35 of the frame which supports and forms a part of the bed spring, 3 the end rails, and 4 transverse bars or rails, which connect the side rails intermediate their ends, all of which parts are preferably made of angle 40 irons, which may be comparatively light and yet afford adequate strength.

6 represents corner irons or plates, which tie the side and the end rails together, and which hold the end rails elevated above the 45 side rails. The corner irons 6 are secured to the rails by rivets 7. The transverse bars 4 are also preferably secured to the side rails in the same manner.

The mattress is supported by a coarse, 50 mesh wire fabric A, which is arranged in longitudinal and transverse strands, comprising links 8 and 9, which are preferably connected by perforated plates 10, to which the links are attached by means of integral hooks 11. Any suitable construction may 55 be followed for producing the fabric. The

fabric A is supported at its opposite ends by a series of novel depending levers 12, which are preferably made out of heavy wire. Each of the adjusting levers 12 comprises an inverted L-shaped part having an arm 13, which is formed by doubling the wire for providing a loop 14 at one end of the arm, which receives the hook 11 of an end link 8 of the fabric, and a loop 14' adjacent the loop 14. The opposite end of each arm 13 is formed into a hook 15, which engages a perforation in the end rail 3 for hinging or pivoting the levers to the frame. The wire comprising the lever 12 is then 60 coiled around the arm 13 between the loop 14' and the hook 15, from which it extends downwardly and its lower end is then bent upon itself and formed into a letter S, for providing two loops, 16 and 17.

18 represents a brace also preferably consisting of wire, one end of which has a loop 18' through which arm 13 passes, the said loop being positioned between the loops 14 and 14' of said arm, which holds the brace 70 in place, the opposite end of the brace having a hook 19 which engages the loop 16 of the long arm of the lever 12.

20 represents a relatively large and stout tension spring, which connects to the loop 17 80 of the lever 12 by means of a hook 21, the opposite end of the spring 20 having a hook 22 which engages a perforation in one edge of a floating lever or bar 23.

24 represents a series of tension-rods, each 90 having a hook at one end to engage perforations in the opposite edge of the lever 23. The rods 24 then pass loosely through suitable perforations in the transverse bars 4, and their opposite ends are threaded to receive crank-nuts 25, by means of which the levers 23 are pulled toward said bars for stretching the springs 20 for rocking the levers 12 in the direction for increasing the tension of the strands 8 of the fabric A. 100 The springs 20 operate the levers 23 in the opposite direction when the nuts 25 are unscrewed. Each of the longitudinal strands 8 connects at its opposite end with the corresponding levers 12. In practice, there are 105 four of the levers or bars 23, that is to say, two at each end of the frame, and the corresponding levers 23 connect with the corresponding strands 8, so that by turning the crank-nuts 25 at the opposite ends of the 110 frame in the right direction, imparts an even tension to the said strands. The levers 12

are supported solely by the hooks 15 which engage the inner edges of the end rails 3, as described. This leaves their lower ends free to move backward and forward by the flexing of the springs 20. In a full sized bed spring there are seven or eight of the strands 8, levers 12, and springs 20 connected to each pair of the levers 23, as shown, and in the preferred arrangement there are two of the adjusting rods 24 attached to each of the levers 23.

By the construction and arrangement herein shown and described, the strands 8 at one side of the bed, which are connected to the corresponding head and foot levers 23, may be given a comparatively strong or high tension for supporting a heavy person, while the strands 8 on the other side of the bed which are connected to the other set of levers 23, may be given a lighter or weaker tension for supporting a smaller or lighter person. In this way, in a moment's time, my improved spring may be adjusted and set for providing for the comfort of occupants of the same or different weights.

Heretofore the majority of bed springs have had a tendency to sag in the center, even when one person is occupying the bed, and this sagging is still more marked when two persons are occupying the same bed. I overcome this defect or fault in a very simple manner as follows: In case the fabric A of my spring shows a tendency to sag in the middle, I wind up the innermost crank-nut 25 of each of the levers 23, which draws the inner ends of said levers toward the middle of the bed, as shown by dotted lines in Fig. 1. This increases the tension of the strands 8 of the fabric at or adjacent the longitudinal center of the spring, while a normal tension may be left on the strands nearest the opposite sides of the spring. By this means the fabric A will remain substantially level although the occupants lie in the middle of the bed. When a slight increase of the normal tension is required, as when children occupy a bed equipped with my improved spring, it is only necessary to tighten up the nuts 25 at the foot of the bed. But when heavy or grown-up persons are occupying the bed, the nuts 25 at the head and foot should be tightened up, so as to give the required tension to the fabric without unduly straining the springs 20 at either end.

Fig. 5 illustrates a modification of my tension and adjusting means, which consists of eliminating the floating bars 23, and substituting therefor threaded bolts or rods 27, which connect directly to the springs 20, and then wing-nuts 28 are employed for adjusting the rods 27 and controlling the said springs. By this arrangement each of the strands 8 is provided with an independent adjustment, instead of the collective ad-

justment shown in the preceding figures of the drawing.

It is obvious that the levers 12 may be constructed out of sheet or cast metal, and that the number and arrangement of the various tension and adjusting parts may be varied or modified, within the scope defined by the appended claims, without departing from the spirit of the invention.

Having thus described my invention, what I claim as new and desire to secure by Letters Patent, is—

1. In a bed spring, a frame, a fabric, rocking levers hinged to the frame and also to the fabric, floating bars, means for operatively connecting said bars to said levers, and means for operating said bars for rocking said levers.

2. In a bed spring, the combination with a fabric for supporting a mattress and a frame, of a plurality of tension levers hinged to each end of the frame and connected to the ends of the fabric, a series of floating bars, resilient means connecting said bars to said levers, and screw-bolts for operating said bars and said levers.

3. The combination of a fabric for supporting a mattress, a frame, a plurality of tension levers connecting said fabric to said frame, a plurality of floating bars, tension springs interposed between said floating bars and said tension levers, and means for operating said levers and said bars for increasing and decreasing the tension of said fabric.

4. In a bed spring, a frame, a fabric for supporting a mattress mounted in said frame, a plurality of depending levers hinged to the end rails of the frame and supporting the ends of the fabric, a series of tension springs connected to said depending levers, and a series of rods for increasing and decreasing the tension of said springs.

5. In a bed spring, a frame, a fabric for supporting a mattress above said frame, a plurality of tension levers pivoted to the end rails of said frame and connected to the ends of said fabric, springs connected to the lower ends of said tension levers, floating bars connected to said springs, and means for independently operating each of said bars for increasing the tension of certain parts of said fabric without disturbing the other parts thereof.

6. A bed spring, comprising a frame, a fabric for supporting a mattress mounted above said frame, levers supported by the ends of said frame and connected to the ends of said fabric, a series of floating bars disposed beneath said fabric and connected with said levers, and a series of rods connected to said floating bars adapted to pull said levers toward the middle of the fabric for increasing the tension of the same.

7. In a bed spring, a frame comprising

end rails and cross-bars, a fabric for supporting a mattress mounted between said end rails, levers pivoted to the end rails of the frame and connected to the ends of the fabric, floating bars, tension springs connecting said floating bars with the said bars, rods piercing said cross-bars, said rods connecting to the floating bars, and crank-nuts

carried by said rods for increasing and decreasing the tension of said springs. 10

In testimony whereof I affix my signature in presence of two witnesses.

RICHARD J. KELLY.
